UNITED STATES PATENT OFFICE

CHARLES LIONEL MARCUS, OF NEW YORK, N. Y.

DESIGN FOR A LIP STICK OR SIMILAR ARTICLE

Application filed January 30, 1930. Serial No. 34,347. Term of patent 14 years.

To all whom it may concern:

Be it known that CHARLES LIONEL MARCUS, citizen of the United States, and resident of New York city, in the county of New York and State of New York, has invented a new, original, and ornamental Design for Lip Stick or Similar Article, of which the following is a specification, reference being had to the accompanying drawing, forming part thereof, in which,

Fig. 1 is a top plan view of a lip stick embodying the invention; and

Fig. 2 is a side elevational view of the lip stick.

I claim:

The ornamental design for a lip-stick or similar article as shown.

Dated, New York, January 24th, 1930.

CHARLES LIONEL MARCUS.
